US0D1105739S

(12) **United States Design Patent** (10) **Patent No.:** **US D1,105,739 S**
(45) **Date of Patent:** **** Dec. 16, 2025**

(54) **BACKPACK**

(71) Applicant: **Hui Hu**, Guangzhou (CN)

(72) Inventor: **Hui Hu**, Guangzhou (CN)

(**) Term: **15 Years**

(21) Appl. No.: **29/996,424**

(22) Filed: **Apr. 1, 2025**

(51) **LOC (15) Cl.** **03-01**

(52) **U.S. Cl.**
USPC **D3/217**

(57) **CLAIM**

The ornamental design for a backpack, as shown and described.

DESCRIPTION

FIG. 1 is a perspective view of a backpack, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All the broken lines in the drawings depict portions of the backpack that form no part of the claimed design.
